UNITED STATES PATENT OFFICE.

PERCY EDMOND CHEESMAN, OF WEST CROYDON, LONDON, ENGLAND.

MECHANISM FOR RELEASING DETONATOR-STRIKERS IN PROJECTILES.

1,294,047.

Specification of Letters Patent. Patented Feb. 11, 1919.

Application filed April 18, 1918. Serial No. 229,364.

To all whom it may concern:

Be it known that I, PERCY EDMOND CHEESMAN, a subject of the King of Great Britain, residing at 14 Sydenham road, West Croydon, London, England, have invented new and useful Improved Mechanism for Releasing Detonator-Strikers in Projectiles, of which the following is a specification.

This invention relates to improved means for releasing the detonator strikers of projectiles.

According to this invention the striker which is normally under the action of a loaded spring in the safety position is released from this position by centrifugal force but is prevented from striking until centrifugal force has ceased to act.

The accompanying drawings show mechanism made in accordance with this invention and fitted to a Mills grenade of the ordinary service type. Figure 1 is a longitudinal section and Fig. 2 an end view of the grenade. Fig. 3 is an end view of the split tube with the weight at one end of it, the striker being in the safety position. Fig. 4 is an elevation, Fig. 5 a plan and Fig. 6 an end view of one part of the split tube while Figs. 7, 8 and 9, are similar views of the other part. Fig. 10 is a part side elevation and Fig. 11 an end view of a tool for assembling the parts together.

A is a striker around whose stem is coiled a spring B attached at one end to the striker at C and at the other end to a ring D formed in one with one part E of the split tube and having a slot D¹ to allow the passage of a pin F on the striker A. In the other part H of the split tube are slots G, G¹, to allow the passage of the pin F and at the end of the slot G¹ is a recess G² in which the pin F is retained. On the outer surface of the two parts E and H of the split tube are projections I, I¹, and J, J¹, respectively, by means of which weights E¹ and H¹ are secured to the parts E and H respectively. The split tube and the weights are inclosed in a tube K capable of being fitted in a grenade L and secured there by a plug M. At the inner end of the tube K is a stop N held in the position shown in Fig. 1 by a spring N¹ on a stem N² which is secured to the stop and extends outside the wall of the grenade. Normally the stop N is pressed against the end of the split tube by an arm O of usual construction which is held in contact with the end of the stem N² by means of a split

pin P which passes through holes O¹ in the arm O and holes L¹ in the grenade L. On the arm O are projections O² which engage with slots L² in the grenade L.

In assembling the release mechanism the striker is first placed in the part E and the spring B is attached to the ring D. The weight E¹ is then slipped over the end of the part E and the weight H¹ is slipped over the end of the part H and the two parts are slid upon one another, the end of the part E entering the weight H¹ and the end of the part H entering the weight E¹. The striker is then pressed inward by means of the tool shown in Figs. 10 and 11, the pin F on the striker passing up the slots G and D¹ and along the slot G¹, and when the tool is withdrawn the pin F enters the recess G² in the part H, the spring B of the striker A having been compressed and twisted.

When the grenade is thrown so that it rotates about its minor axis, thus causing the weights E¹ and H¹ to move toward the ends of the grenade, the two parts E and H slide upon each other so that the pin F comes opposite to and enters the slot G¹ where it is held by the ring D against the wall of the slot. When the centrifugal force ceases the twist given to the spring causes the pin F to pass along the slot G¹ and the two parts of the split tube slide upon each other, the pin F, under the action of the spring, passing down the slot G and thus allowing the striker to hit a pellet Q.

What I claim is:—

1. In combination with a projectile, a striker and a spring which engages the striker and which is twisted and compressed when the striker is in the safety position, said striker being released from said safety position by centrifugal force but prevented from striking until the centrifugal force ceases to act.

2. In combination with a projectile, a striker and a tube split longitudinally into two parts and inclosing the striker and so arranged that one part is adapted to be moved upon the other by centrifugal force.

3. In combination with a projectile, a striker, a tube split longitudinally into two parts and inclosing the striker, the two parts of the tube being so arranged that one part is adapted to be moved upon the other by centrifugal force, and a spring attached to the striker and one part of the tube.

4. In combination with a projectile, a

striker, a tube split longitudinally into two parts and inclosing the striker, the two parts of the tube being so arranged that one part is adapted to be moved upon the other by centrifugal force, a spring attached to the striker and one part of the tube, a pin on the striker, and a slot in one part of the tube to receive the pin.

5. In combination with a projectile, a 10 striker, a tube split longitudinally into two parts and inclosing the striker and so arranged that one part is adapted to be moved upon the other by centrifugal force, a spring actuated stop adapted to prevent movement 15 of the parts of the tube and means for compressing the spring and moving the stop.

6. In combination with a projectile, a 20 striker, a tube split longitudinally into two parts and inclosing the striker, the two parts 25 of the tube being so arranged that one part is adapted to be moved upon the other by centrifugal force, a spring attached to the striker and one part of the tube, a pin on the striker, a slot in one part of the tube to receive the pin, a spring actuated stop adapted to prevent movement of the parts of the tube and means for compressing the spring and moving the stop.

7. In combination with a projectile, a 30 striker, a tube split longitudinally into two parts and inclosing the striker and so arranged that one part is adapted to be moved upon the other by centrifugal force, an outer tube inclosing the split tube, projections on 35 the split tube and weights engaging with the projections and the outer tube.

8. In combination with a projectile, a 35 striker, a tube split longitudinally into two parts and inclosing the striker, the two parts

of the tube being so arranged that one part 40 is adapted to be moved upon the other by centrifugal force, a spring attached to the striker and one part of the tube, a pin on the striker, a slot in one part of the tube to receive the pin, an outer tube inclosing the 45 split tube, projections on the split tube and weights engaging with the projections and the outer tube.

9. In combination with a projectile, a 50 striker, a tube split longitudinally into two parts and inclosing the striker and so arranged that one part is adapted to be moved upon the other by centrifugal force, a spring actuated stop adapted to prevent movement 55 of the parts of the tube, means for compressing the spring and moving the stop, an outer tube inclosing the split tube, projections on the split tube and weights engaging with the projections and the outer tube.

10. In combination with a projectile, a 60 striker, a tube split longitudinally into two parts and inclosing the striker, the two parts 65 of the tube being so arranged that one part is adapted to be moved upon the other by centrifugal force, a spring attached to the 70 striker and one part of the tube, a pin on the striker, a slot in one part of the tube to receive the pin, a spring actuated stop adapted to prevent movement of the parts of the tube, means for compressing the spring and moving the stop, an outer tube inclosing the split tube, projections on the split tube and weights engaging with the projections and the outer tube.

In testimony that I claim the foregoing as 75 my invention I have signed my name this 3d day of April, 1918.

PERCY EDMOND CHEESMAN.
